DESCALING BURNER

Chester Mott, Evanston, and Alfred F. Chouinard and Mitchell A. Tylutki, Chicago, Ill., assignors to National Cylinder Gas Company, Chicago, Ill., a corporation of Delaware

Application August 7, 1945, Serial No. 609,360

14 Claims. (Cl. 263—9)

1

This invention relates to blow pipes or burner apparatus of the type designed and adapted for producing a row of closely spaced high temperature flames for the heat treatment of a surface, as for example, to remove scale, rust or other adhering material from such a surface, or to change such material into easily removable form. Such a burner may, for example, be used in descaling metal blooms in preparation for rolling, or it may be used to remove rust from any metal surface to prepare said surface for painting.

As a feature of the present invention, the burner is mounted on a portable wheeled carriage adapted to be rolled over the surface to be treated. This burner carries a series of tips properly spaced; the proper positioning of these tips and their correct angle with respect to the workpiece being assured by the carriage mounting the burner.

As a further feature, the burner comprises a manifold head having a series of tips easily removable for replacement and cleaning. These tips are desirably made of metal having high heat conductivity, such as copper, are all of the same size and shape as to be interchangeable, and are comparatively long. The relatively long distance that the gas travels in these tips irons out the turbulences in the gas, and results in a smooth gas flow, so that stable flame cones are generated. These comparatively long tips also serve to maintain the burner head away from the surface to be heated, and from the intense heating zone created near the surface, so that destructive overheating of said head is prevented.

Moreover, these long copper tips aid in keeping the burner cool because of the large surface areas exposed to the air, and as a result, these descale a great deal faster than burners hitherto proposed for this purpose.

As a further feature, the burner head has a series of air passages with discharges on opposite sides of the row of tips, and has means for delivering air under pressure to these passages. The air supply through these passages aids in cooling the burner, and the ejected streams, as they are projected against the surface being heat treated, help to remove the scale which was loosened. These air streams blow the scale away from the tips, and help prevent them from becoming clogged with the scale and dirt.

The volume of acetylene used in the burner is relatively high, so that it is difficult to produce a good mixture, using the burner manifold head as a gas mixer. As another feature, there is provided a distributor block separate from the burner head, and a pair of mixers connected to said block for mixing the distributed gases. Thus a proper mixture of gases is obtained with less danger of backfiring and flashback. The two

2

mixers mix the gases, such as oxygen and acetylene in proper proportions, and conduct them through tubes to the burner head.

Various other features and advantages of the invention will be apparent from the following particular description, and from an inspection of the accompanying drawings, in which:

Fig. 1 is a side elevation of a descaling burner carriage assembly embodying the features of the present invention;

Fig. 2 is a top plan view of the lower portion of the assembly;

Fig. 3 is a top plan view of the gas distributor and mixer unit;

Fig. 4 is a front elevation with parts broken away of the gas distributor and mixer unit;

Fig. 5 is a fragmentary side elevation of the gas distributor and mixer unit;

Fig. 6 is a transparent diagrammatic perspective of the burner manifold head showing the air conduit system;

Fig. 7 is a transparent diagrammatic perspective of the burner manifold head showing the conduit system for the combustible mixture of gases;

Fig. 8 is a fragmentary diagrammatic perspective of the burner manifold head showing how the flame tips are attached thereto;

Fig. 9 is a front face view of the burner manifold head;

Fig. 10 is an end view of the burner manifold head;

Figs. 11, 12 and 13 are transverse sections taken on lines 11—11, 12—12 and 13—13 of Fig. 9, respectively; and

Fig. 14 is a section taken along lines 14—14 of Fig. 9, but on a larger scale.

The burner assembly shown in the drawings comprises in general a wheeled carriage 10 (Figs.

40 1 and 2), an elongated hollow inclined handle 11 secured at its lower end to the frame structure of the carriage and carrying inside thereof, gas connections to the burner, a valve unit 12 near the upper end of said handle 11 for controlling flow through said connections, a gas distribution

45 block 13 near the lower end of said handle, a pair of gas mixers 14 connected to said distributor block, a manifold burner block or head 15 supported on the forward section of the carriage 10

and supplied with a combustible gas mixture

50 from the mixers 14 and with air from the distributor block 13, and a series of flame tips 16 connected to the burner block 15 and adapted to project their flame cones onto the surface to be descaled or otherwise heat treated.

55 The carriage 10 comprises a pair of similar side frame members 20, each having upwardly converging end sections 21 and a central horizontal top section 22. Secured to the ends of the frame

members 20 are two axles 23, and mounted on each of these axles is a pair of wheels 24. The side frame members 20, the axles 23 and the wheels 24 thereby form a light, low portable truck.

The carriage truck is secured to the handle 11 by means of a pair of inclined side frame members 26 having lower parallel sections 27 straddling the forward inclined end sections 21 of the frame members 20 in substantial inclined alignment therewith, and rigidly secured thereto, as for example, by welding. The intermediate sections 28 of these side frame members 26 converge towards the base of the handle 11, and the upper ends 30 of these side frame members extend in substantially spaced parallel relationship, and are made fast to the handle in a manner to be described. Mounted between these upper frame ends 30 is the gas distributor block 13, supplied with a combustible gas such as acetylene by a pipe connection 32, supplied with a combustion supporting gas, such as oxygen, by a pipe connection 33, and supplied with air by a pipe connection 34. These three pipe connections 32, 33 and 34 are mounted in the handle 11, and are respectively controlled by the valve unit 12 near the upper end of said handle. Flexible hose connections (not shown) are provided to this valve unit 12 from the different tanks or other sources of gas supply.

The distributor block 13 is secured to the handle 11 by means of a flange 40 affixed to the top of the block, as for example, by studs 41, and having a sleeve extension 42 snugly embracing the lower end of the handle 11, and secured thereto by screws 43 or other suitable means. The upper ends 30 of the side frame members 26 are made fast to this flange 40 by suitable means, as for example, studs 44.

The distributor block 13 (Figs. 3, 4 and 5) is bored to define the different flow passages. The flow circuit for the acetylene in this block includes an inlet passage 50, to which the supply pipe 32 is fitted, extending from the top of the block partway down, and connecting into the midsection of a manifold passage 51 extending from end to end of said block. To facilitate the machining of this manifold passage 51 in the block 13, this passage is formed by boring right through the block and then closing the ends of the bore, as for example, by suitable sealing brazed plugs 52.

The distributor block 13 has at its lower end two cylindrical branch extensions 53 to which the two mixers 14 are connected in a manner to be described. Each of these block extensions 53 has an annular groove 54 in which the acetylene is collected and distributed to the mixing chamber of the corresponding mixer 14, as will be described. The acetylene is delivered from the manifold passage 51 to each of these two collecting grooves 54, one in each cylindrical extension 53, by a series of outlets 55, four being shown for each mixer 14 circumferentially arranged and extending from said manifold passage 51 through the corresponding block extension 53, and to said collecting groove.

The flow circuit for the oxygen in the distributor block 13 includes an inlet passage 60 to which the supply pipe 33 is connected, extending from the top of the block partway down, and having two branches 61 diverging downwardly through the main body of the block, and through its extension 53. At their lower ends, each of these oxygen branch passages 61 connects into an outlet opening 62 centrally located with respect

to the acetylene collecting groove 54, and communicating with the mixing chamber of the corresponding mixer 14, as will be described.

Each of the gas mixing units 14 comprises an upper cylindrical shoulder 65 fitting snugly into a corresponding recess 66 in the lower end of the distributor block extension 53, and a neck 67 fitting snugly into the oxygen outlet 62 in said extension. The mixer 14 is removably clamped to the distributor block extension 53 by means of a nut 70 engaging an annular flange 68 on said mixer 14 and threaded onto said extension. A gas sealing washer 69 fits between mixer 14 and distributor block 13, to prevent intermingling of the two gases, prior to proper mixing, as will be described below.

The shoulder 65 on the mixer 14 has an annular groove 71 opposite to and in direct communication with the acetylene collecting groove 54, and the mixer has a central passage 72 connecting with said groove 71 by a series of inclined ports 73 annularly arranged around said central passage, so that acetylene is delivered to said central passage. The central passage 72 communicates at its upper end directly with the oxygen outlet 62, so that oxygen is also delivered to said passage. The cross-section of the passage 72 is increased progressively towards the outlet end of the mixer 14, and by the time the oxygen and acetylene reach the outlet 75 of this passage, these gases are thoroughly intermixed. The combustible mixture of gases is delivered by two pipe connections 74 from the two outlets 75 of the mixers 14 to the inlets of the manifold burner head 15.

The distributor block 13 is also employed to distribute air to the burner for the purpose to be further described. To that end, the distributor block 13 has at the top an inlet air passage 76 to which the supply pipe 34 is connected, extending downwardly to the center of a passage 77, which extends from the front to the back of the block, and which is formed by boring completely through the block and sealing the ends 80 of the bore, as for example, by plugging and brazing. The ends of the passage 77 connect with the ends of two passages 81 extending along the front and rear of the block 13, and formed by boring through from one side of said block, and sealing the ends 82 of said passages 81, as for example, by plugging and brazing. Each of the passages 81 has two outlets 83, so that the distributor block 13 has an air inlet 76 at the top of the block, two air outlets 83 at the front, and two air outlets 83 at the rear. The air is delivered by four pipe connections 85 (Figs. 1 and 2) from these four air outlets 83 to the air inlets of the manifold burner block 15.

The manifold burner block or head 15 (Figs. 1 and 2) is of elongated construction, and is desirably of right pentagonal cross-section, so that the block has parallel plane side faces 90, a plane front face 91, and plane upper and lower rear angular faces 92. This burner block 15 is removably mounted on the carriage frame desirably by means of a plurality of U-shaped straps 93, three being shown, shaped to conform with the cross-section of the block, and straddling with a snug fit the rear angular faces 92 and the parallel side faces 90 of the block. The ends of the straps 93 have outwardly extending flanges 94. Connected to each of the two end straps 93 and extending across the front face 91 of the block 15 at the end is a bracket 95 having an upper end flange extension 96 secured to the corresponding strap flange 94 by a screw 97 and a pair

of lock nuts 98 on said screw, and having a similar lower end flange extension 96 similarly secured to the corresponding strap flange 94 by a screw 101 and locknuts 98. The middle strap 93, instead of having a single bracket secured thereto and extending across the front block face 91, has two brackets 103 connected to the end flanges 94 of said middle strap respectively by the screws 97, 101 and nuts 98, and engaging only the marginal sections of the block face 91. With this construction, there is no blocking of the different outlets leading to said face 91, or interference with the uniform spacing of these outlets along the full length of the block 15.

The two rows of screws 97 and 101 serve not only as a means for clamping the block-attaching elements 93, 95 and 103 to the block 15, but also serve as guards to protect the flame tips, as will be made more apparent.

Secured to one of the angular sections of each of the two end or outside straps 93 is a bracket 105 in the form of an angle having a flange base which is secured to said angular strap section by any suitable means, and having its other flange removably secured to the rear section 21 of the corresponding side frame carriage member 20, as for example, by a screw 106. Secured to the upper side section of each of the two end or outside straps 93 is a second bracket 107 in the form of an angle having a flange base which is secured to said side strap section by any suitable means, and having its other flange removably secured to the horizontal top section 22 of the corresponding side frame carriage member 20, as for example, by a screw 108. In this manner, the burner manifold block 15 can be easily removed for repair or in case it is desired to replace it by a burner block of different length to conform with the width of the surface to be described. In operative supported position, the front face 91 of the block 15 will extend at an angle with the upper surface of the workpiece, so that the flame tips 16 connected to said block face will extend obliquely downwardly towards said surface at a correct angle, as will be more fully described.

The burner manifold block 15 is formed with various passages for the flow of the combustible mixture of gases. For that purpose, the upper rear angular side 92 (Figs. 7, 12) of said block has two inlet passages 115 connected to the outlet ends of the two pipe connections 74 leading from the outlets 75 of the two gas mixers 14. Each of these inlet passages 115 transversely extends part way into the block 15 and connects into a passage 116 extending lengthwise of the block towards one end of said block. At this end of the block 15, there are two short diverging branch passages 117 connecting the passage 116 with two parallel manifold passages 118 extending longitudinally of the block near the front block face 91 and towards the midsection of said block. There are thereby provided in the burner block 15 four manifold passages 118 arranged in two pairs extending in parallelism alongside of each other, each pair consisting of two passages 118 in axial alignment. To facilitate the machining of the different passages, the block 15 is bored or drilled from its angular faces 92 and ends, and the ends of the bores are sealed by screw plugs 120.

Each of the manifold passages 118 has connected thereto a series of outlet ports 121 extending to the front face 91 of the block 15, and threaded into each of these outlet ports is a flame tip 16. In order to equalize the pressure of the gas mixture along the length of each manifold

passage 118 and thereby equalize the rate of discharge from the different outlet ports 121 connected thereto, these passages taper towards the center of the blocks, as shown in Fig. 7.

The outlet ports 121 are equally spaced along one straight row lengthwise of the block 15, and two of such straight rows are formed in parallel relationship. In order to form a continuous flame sheet by the conjoint action of the two rows of tips 16, the outlet ports 121 in one row are staggered with respect to the outlet ports in the other row, as shown in Fig. 9, and the plane of the axes of the ports in one row is inclined away from the block towards the plane of the axes of the ports in the other row, the inclination of these two converging axes planes being such that the ends of all the flames are on a single straight line parallel to the longitudinal axis of the block, as shown in Figs. 8 and 14.

The tips 16, which are all of the same size and shape, are desirably of copper, so that they effectively cool the burner, and are comparatively long, projecting as much as 2½ inches or more from the outlet face 91 of the block 15. These tips 16 taper at their outer ends, and can therefore be placed fairly close together alongside of each other at these ends to produce a continuous flame sheet. The tips 16 are desirably swaged to shape, this swaging process making it possible to produce a better tip and consequently a better flame. For effective descaling operations, the flames produced by these tips 16 are desirably of the so-called semi-blunt type.

Air is circulated through different passages in the manifold block 15 for cooling purposes, and is projected against the surface of the workpiece being treated to remove the slag loosened or formed by the action of the flames. The air circuit through the block 15 comprises four inlet passages 129 and 130 spaced along its upper inclined face 92, and connected to the four air supply connections 25 leading from the distributor block 13. The two inside inlet passages 129 connect transversely of the block into two passages 131 respectively, extending longitudinally along the block 15 towards their ends. At the ends of the block 15, these passages 131 connect by short transverse passages 132 with the end of a manifold passage 133 extending near the front block face 91 along the length of the block on one side thereof. A row of small outlet air holes 134 extend from the manifold passage to the front block face 91.

The two outside inlet passages 130 connect transversely of the block into two passages 135 respectively, extending longitudinally along the block 15 towards their ends. At the ends of the block 15, these passages 135 connect by short transverse passages 137 with the end of a manifold passage 138 extending near the front block face 91 along the length of said block on the side thereof opposite the air manifold passage 133. A row of small outlet air holes 140 extend from the manifold passage 138 to the front block face 91.

To facilitate machining operations in forming the different air passages in the burner block 15, some of the air passages are formed by drilling or boring from the faces and ends of the block 15, and sealing the ends of these passages at these block faces and ends by plugs 141 desirably brazed in.

The two rows of outlet air holes 134 and 140 are parallel, and extend along the block 15 on opposite sides of the two rows of mixed gas out-

lets 121. These air holes 134 and 140 in the two rows extend substantially parallel, and project the air against the workpiece in planes substantially parallel to the plane of the flame sheet. Due to the comparatively long distance between the air holes 134 and 140, and the surface of the workpiece, the streams from the holes in each row merge before they reach said surface, and strike said surface as a continuous curtain stream, so that a more effective sweeping action by the ejected air is assured.

The oxygen and acetylene for the gas mixture, and the air for the cooling and sweeping operation is supplied through the respective valves in the valve unit 12 (Fig. 1) at the upper end of the handle 11. This valve unit comprises a combination of a quick shut-off valve and valve assembly similar to that shown in copending application Serial No. 597,300. Member 150 is a lever which must be pressed down before gas can pass to the pipe connections 32 and 33. This lever 150 is locked down by a catch in the handle 11. In the event of a backfire or a flash-back, the operator may quickly shut off the supply of gas and remove the danger of serious damage. The quick shut-off valve is also used to shut off the gas when work is stopped for some reason. Once the two valves 151 controlling flow of the two connections 32 and 33 respectively are adjusted, the quick shut-off valve may be used for starting and stopping the burner without the necessity of readjusting these two valves.

By means of the carriage burner mounting of the present invention, the tips 16 are properly spaced above the workpiece and at the correct angle.

These tips 16 are effectively protected against injury in the front by the three adjustable long guard screws 97 and in the rear by the three adjustable short guard screws 101. With this guard arrangement any abrupt bumps in the formation of the surface being treated, or any raised member in the path of the tips 16 will not strike these tips. The burner manifold blocks 15 may be built in different lengths having the same cross-sections and same size tips 16 attached thereto, and these blocks may be interchangeably mounted on the same carriage according to the width of the surface to be descaled. For example, the burner may be built in three sizes, 8", 10" and 12". The number of tips 16 in each of these burners varies according to the size of the burner. For instance, a 12" burner may have 33 tips in one row and 32 tips in the other row, making a total of 65 tips.

To change the burner size, it is only necessary to remove the four screws 106 and 108 attaching the bracket assembly of the burner block 15 to the carriage frame, and to loosen the six union connections between the pipes 74, 85 and the burner manifold block inlets 115, 129 and 130.

The screw plugs closing the ends of the passages in the burner manifold block 15 may be removed for cleaning these passages.

Since the volume of acetylene used in the burner is relatively high, a better mixture of these gases is obtained with less danger of back-firing and flash-back by using two mixers.

The relatively long distance that the gas travels in the tips 16 prevents the gas from becoming turbulent, and results in a smooth gas flow and stable flame cones.

As many changes can be made in the above apparatus, and many apparently widely different embodiments of this invention can be made

without departing from the scope of the claims, it is intended that all matter contained in the above description or shown in the accompanying drawings shall be interpreted as illustrative and not in a limiting sense.

Having thus described our invention, what we claim as new and desire to secure by Letters Patent is:

1. A burner for progressively heating a metal member along the surface thereof, said burner including a burner head having two separate parallel passages for an oxygen-acetylene mixture and two rows of tips, each row leading from a separate passage, and the tips of each row being slightly inclined toward those of the other row and being of such length as to align the outlet ends of all of said tips in substantially a single straight line extending lengthwise of said burner head.
- 10 2. A burner for progressively heating a metal member along the surface thereof, said burner including a burner head having two separate parallel passages for an oxygen-acetylene mixture and two rows of tips, each row leading from a separate passage, and the tips of each row being slightly inclined toward those of the other row, the outlet ends of the tips of the two rows being arranged alternately and closely spaced together in substantially a single straight line to cause the flames from all of the tips to be projected in substantially the same direction to form substantially a single continuous sheet of flame.
- 15 3. A burner having an elongated body member provided with a pair of passages extending lengthwise thereof, a pair of oxygen-acetylene mixers, means for delivering the gas mixture from one mixer to one end of one of said passages, and means for delivering gas mixture from the other mixer to one end of the other passage, and means including two rows of elongated tips, each row being separately supplied with gas mixture from said passages, the tips of the two rows being in planes at a small angle to each other and the delivery ends of the tips of both rows being closely juxtaposed to deliver gas into substantially a single plane extending lengthwise of said body member.
- 20 4. A burner having an elongated body member provided with a pair of passages extending lengthwise thereof, a pair of oxygen-acetylene mixers, one of said mixers being connected to one end of said body for feeding gas mixture to one end of one of said passages, and the other mixer being connected to the other end of said body for feeding gas mixture to the other end of the other passage, and two rows of elongated tips, each row being separately supplied with gas mixture from said passages, and the tips of the two rows being in planes at a slight angle to each other and the ends of said tips being substantially in a single row and alternately arranged to deliver gas mixture from all of said tips into substantially a single plane extending lengthwise of said body member.
- 25 5. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 30 6. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 35 7. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 40 8. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 45 9. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 50 10. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 55 11. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 60 12. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 65 13. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 70 14. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.
- 75 15. A burner having an elongated body member provided with a pair of passages extending lengthwise thereof, said passages being substantially in alignment, means for delivering an oxygen-acetylene mixture to the outer ends of both passages, and means including two rows of elongated tips separately supplied with gas from said passages, the tips of the two rows being in planes slightly inclined toward each other and the outlet ends of all of said tips being substantially in a single row and alternately arranged to deliver gas mixture from all of said tips into substantially a single plane extending lengthwise of said body member.

tially in a single straight line extending lengthwise of said body member.

6. A burner having an elongated body member provided with a pair of passages extending lengthwise thereof and each having a row of delivery tips inclined toward those of the other row to align the outlet ends of all of said tips substantially in a single straight line, said passages being substantially parallel and of progressively decreasing diameter inwardly from the outer end thereof, and means for delivering an oxygen-acetylene mixture to the outer ends of both passages.

7. A burner having an elongated body portion provided with a pair of mixture passages extending lengthwise thereof, two rows of tips, one leading from one of said passages and the other leading from the other of said passages, the tips of one of said rows being slightly inclined to those of the other row, and the outlet ends of the tips of both rows being substantially in a single straight line, a gas mixer, and means for connecting said gas mixer to one end of one of each of said passages.

8. A burner for progressively heating a metal member along the surface thereof, said burner including a burner head having two separate parallel passages for an oxygen-acetylene mixture and two rows of tips, each row leading from a separate passage, and the tips of each row being slightly inclined toward those of the other row and of such length that the outlet ends of said tips are disposed in substantially a single straight line, said burner head also having a passage extending lengthwise thereof and provided with outlet openings in the face bearing said tips, and means for delivering air through said last mentioned passage.

9. In an apparatus for heat treating a metal surface having a carriage, a handle connected thereto, a gas distribution block carried by said handle, conduits extending lengthwise of said handle and connected to said block for supplying separately oxygen, acetylene and air thereto, the combination of a pair of mixers connected to said block for receiving and mixing oxygen and acetylene to form a combustible gas mixture, a burner having an elongated body member secured to said carriage and provided with a pair of passages for said gas mixture and an air passage extending lengthwise thereof, conduit means connecting one of said mixers with each of said gas passages and for supplying air to said air passages, two rows of elongated tips carried by one face of said elongated body member, the tips of each row being supplied with gas mixture from one of said gas passages and being inclined toward those of the other row and alternately arranged to align the outlet ends of the tips in substantially a single straight line extending lengthwise of said body member, and a row of air outlets from said air passage in the face of said body member bearing said tips.

10. In an apparatus for heat treating a surface having a carriage, a handle for propelling said carriage and having separate passages extending lengthwise thereof for oxygen and for a combustible gas, the combination of a pair of gas mixers secured to said handle and each connected to both of said passages, a burner block on said carriage having a plurality of manifold passages extending lengthwise thereof and provided with outlets along the length thereof, means connecting one of said mixers to one of said passages and means for connecting the other of said mixers to another of said passages, and

means including converging elongated tips to deliver gas mixture from each of said outlets into substantially a single plane extending lengthwise of said burner block.

5 11. In an apparatus as defined in claim 10, in which said manifold passages are in axial alignment and are of progressively decreasing cross-sectional area inwardly from the gas receiving end.

10 12. An apparatus for heat treating a metal surface, including a portable frame, a burner body extending transversely of said frame and having a row of nozzles directed toward the surface to be treated, means for supporting said frame and the burner nozzles carried thereon in spaced relation to the surface to be treated, said supporting means being located both in advance and behind the burner body for effecting relative movement thereof with respect to the surface to be treated, and a plurality of guard means for protecting the tips of said burner nozzles, each of said guard means being supported by said frame adjacent to one of said burner nozzles but spaced therefrom and directed toward the surface to be treated, the terminal portion of each of said guard means being located at a point closer to the surface to be treated than the tip of the adjacent burner nozzle.

30 13. An apparatus as defined in claim 12 in which said guard means are adjustable toward and away from the surface to be treated.

35 14. An apparatus as defined in claim 12 in which a plurality of pairs of guard means are supported by said frame with the two guards of each pair on opposite sides of one of said burner nozzles adjacent thereto but spaced therefrom and directed toward the surface to be treated, the terminal portions of each of said guard means being located at a point closer to the surface to be treated than the tip of the adjacent burner nozzle.
